CLAIM

The ornamental design for an icon for a display screen, as shown and described.

DESCRIPTION

FIG. 1 is a front view of a first image of an icon for a display screen, showing my design;

FIG. 2 is a front view of a second image thereof;

FIG. 3 is a front view of a third image thereof; and,

FIG. 4 is a front view of a fourth image thereof.

The broken lines showing of the display screen are for the purpose of illustrating environmental structure and form no part of the claimed design.
